CLAIM

The ornamental design for a display screen with virtual three-dimensional shoe icon or display system with virtual three-dimensional shoe icon, as shown and described.

DESCRIPTION

FIG. 1 is a front view of a display screen with virtual three-dimensional shoe icon in which the shoe icon is shown in a perspective orientation;

FIG. 2 is another front view thereof, showing a side orientation thereof;

FIG. 3 is another front view thereof, showing an opposite side orientation thereof;

FIG. 4 is another front view thereof, showing a front orientation thereof;

FIG. 5 is another front view thereof, showing a rear orientation thereof;

FIG. 6 is another front view thereof, showing a top orientation thereof;

FIG. 7 is another front view thereof, showing a bottom orientation thereof;

FIG. 8 is a front view of a display system with virtual three-dimensional shoe icon shown in a perspective orientation, the virtual three-dimensional shoe icon being the same design as shown in the first embodiment of FIGS. 1-7; FIG. 9 is another front view thereof, showing a side orientation thereof;

FIG. 10 is another front view thereof, showing an opposite side orientation thereof;

FIG. 11 is another front view thereof, showing a front orientation thereof;

FIG. 12 is another front view thereof, showing a rear orientation thereof;

FIG. 13 is another front view thereof, showing a top orientation thereof; and,

FIG. 14 is another front view thereof, showing a bottom orientation thereof.

In FIGS. 1-7, the outermost broken line represents a display screen which forms no part of the claimed design. In FIGS. 8-14, the outermost broken line represents a portion of a field of view for a visual display and forms no part of the claimed design. In FIGS. 1, 5, 6, 8, 12, and 13, the broken
